LAMP

Application filed August 21, 1929. Serial No. 387,383.

The present invention relates to lamps and is more particularly directed toward a portable lamp such as a table lamp provided with an illuminated column.

5 The present invention contemplates the provision of a table lamp having main light sources such as a cluster of lamps inside the shade. This lamp cluster is supported above a standard which carries a column or cylinder of light transmitting material. Provision is made for illuminating the upper end of this cylinder so that it glows with a dim light.

10 The present invention contemplates that this lighted column may be available independent of the lighting of the main lamps and that the intensity of the light coming out of the column can be regulated. It also contemplates that the same lamp which is employed for lighting the column may by variation of a small shade or reflector, be employed to provide a dim light inside the main shade when the main or large lamps are extinguished.

15 25 The accompanying drawings show, for purposes of illustrating the present invention, one of the many possible embodiments in which the invention may take form, it being understood that the drawings are illustrative of the invention rather than limiting the same.

In these drawings:

20 Figure 1 is a side elevational view of a table lamp with parts in section; Figure 2 is a horizontal sectional view of the standard or column taken on the line 2—2 of Figure 1;

25 Figure 3 is an enlarged fragmentary vertical sectional view; and

30 Figure 4 is a wiring diagram.

As shown in the present drawings, the invention is employed in a table lamp. It has a base indicated at 10 and a metal column or standard indicated at 11. This column or standard is as here shown provided with three vertical supporting parts or straps 12 of suitable ornamental configuration. Near the lower end of these straps, the standard may if desired, be provided with the grill 13.

35 40 45 50 The column or standard is made open inside

the straps 12 and the grill 13 to accomodate a column or cylinder 14 of light transmitting material such as crystal glass of various colors, clear synthetic resins in different colors, moulded casein products in clear colors, or the like.

55 A sheet metal plate 15 is carried at the upper ends of the metal standard. This plate is held in place by screws 16 threaded into the upper ends of the straps 12 or into a ring 17 which may connect them together. The plate 15 is provided with a central aperture 18 preferably slightly smaller than the diameter of the transmitting column 14. The plate 15 is surmounted by a frame 19 consisting of three tubular columns 19a, 19b and 19c. These columns support a cluster head 20 of any desired form of construction.

60 65 70 75 This cluster head carries an upwardly extending shade supporting stem 21 and a number of medium base lamp sockets indicated at 22. The cluster body also carries a downwardly extending centrally located stem 23 to which is attached a lamp socket 24. This lamp socket is preferably a pull chain intermediate base socket, and is provided with a cylindrical cover 25 preferably permanently secured to it. The cover carries a slidable deflector or shade 26.

80 85 90 95 100 In wiring up the lamp, the supply wires are brought in under the base 10 and the wires for the main lamps in the sockets 22 are connected through a switch 30. The lead from the switch 30 extends up through a groove 31 in the back of one of the supporting straps 12, then passes through a wire way 32 in the ring 17 and is carried through a hole in the plate 15 and up through the tubular frame member 19c into the splicing chamber for the cluster 20. This wire is indicated at 32 in Figure 4. It is connected to both the lamp sockets 22. The lead wires from these lamp sockets are connected with a common return lead 33 which passes down through the tubular member through a passage 31 inside another strap 12 and into the base of the lamp. The circuit for the lamp socket 24 is indicated at 35. It passes up through the grooves and tubular frame member as before and then passes down through the short nipple 23 of

the socket. The return from the socket is connected onto the lead 33. The circuit for the major lamps may be turned off and on by the switch 30 in the ordinary manner, while the small lamp 36 in the small socket is controlled by the pull chain independently of the control of the other two lamps. It will, of course, be understood that this is merely one switching arrangement which may be used. One can use a conventional three position switch to separately control the lamps.

The socket 24 and associated parts are carried inside the frame members 19a, 19b and 19c. The light emitted from the small central lamp 36 passes downwardly through the hole 18 in the stamping 15 and into the upper end of the light transmitting column 14. This causes the exposed surfaces of the column to glow at low intensity so that it is visible between the metal columns or straps 12 and through the grill 13. When one desires to obtain general illumination from the lamp 36, the shield 26 may be moved up to the dotted line position as indicated in Figure 1. The plate 15 cuts off direct light from the lamp 36 and assists in bringing the supporting straps 12 and grill 13 into relief when the light is concentrated onto the column 14.

It is obvious that the invention may be embodied in many forms and constructions within the scope of the claims, and I wish it to be understood that the particular form shown is but one of the many forms. Various modifications and changes being possible, I do not otherwise limit myself in any way with respect thereto.

What is claimed is:

1. In a lamp, a standard comprising metal supporting parts and an interposed column of translucent material, the supporting parts being separated to expose the sides of the column, a lamp bulb carried adjacent the end of the column and adapted to cast direct light on the end of the column which retransmits and diffuses the light so that the exposed surface of the column glows, an opaque shield carried at the upper end of the standard, the shield being apertured to permit light to reach the column and acting to cut off extraneous light whereby the supporting parts receive no direct light from the lamp bulb, a small adjustably supported reflector about the lamp bulb, and a large shade outside the reflector and shield, the reflector acting to concentrate the light onto the end of the column or to allow it to fall on the shield which scatters it inside the shade.

2. A portable lamp having a base, a supporting standard provided with a column of light transmitting material, main and auxiliary lamps, a reflector about the auxiliary lamp, means for separately controlling the lamps, and a shade about the main lamps, the auxiliary lamp being disposed directly

above the end of the column whereby the column glows when the auxiliary lamp is lighted and the main lamps are extinguished, the reflector being adjustable to provide for dim general illumination as well as illumination of the column.

Signed at Meriden, in the county of New Haven, and State of Connecticut, this 19th day of August, 1929.
